UNITED STATES PATENT OFFICE.

HENRY W. O'NEILL, OF BROOKLYN, NEW YORK, ASSIGNOR TO GRAY NATIONAL TELAUTOGRAPH COMPANY, OF NEW YORK, N. Y., A CORPORATION OF VIRGINIA.

TELAUTOGRAPHIC APPARATUS.

1,128,492.

Specification of Letters Patent.

Patented Feb. 16, 1915.

Application filed February 24, 1912. Serial No. 679,588.

To all whom it may concern:

Be it known that I, HENRY W. O'NEILL, a citizen of the United States, residing at Brooklyn, county of Kings, and State of New York, have invented certain new and useful Improvements in Telautographic Apparatus, fully described and represented in the following specification and the accompanying drawings, forming a part of 10 the same.

This invention relates to improvements in telautographs of the variable current-strength type, such as shown and described, for example, in Letters Patent of the United States No. 954,150, granted to George S. Tiffany April 5, 1910. Such telautographs are usually provided with means for vibrating the pen-moving parts in the instrument while it is receiving, so as to reduce frictional resistance to the movement of such parts at such time. One branch of the present invention has reference to improved means for this purpose. In such telautographs, a direct current generator is sometimes employed as the source of current supply for the main tracer lines connecting a transmitter with the distant receiver, an example of such use being shown and described in the application executed of even 25 date herewith by George S. Tiffany, Serial No. 679,598. These generators give off alternating waves or surges, which, in a telautograph, seriously interfere with the sensitive polarized pen lifter relay which controls the raising and lowering of the receiving pen, in accordance with like movements of the transmitting tracer. The second branch of the present invention has reference to means for absorbing these surges or 40 waves.

In the accompanying drawings—Figure 1 is a diagrammatic view of a station shown, for convenience, in transmitting condition; Fig. 2 is a like view of another station shown, for convenience, as receiving from the station illustrated in Fig. 1.

For convenience, I have, in these drawings, illustrated the improvements constituting my invention in connection with telautographic apparatus shown and described in the aforesaid Tiffany application, but it will be understood, of course, that the present improvements are not to be limited to this particular form of telautographic apparatus. For convenience in the descrip-

tion which will now be given of my improvements, I have applied to the drawings the same reference characters as those applied to corresponding parts in the drawings of the aforesaid application of George S. Tiffany. Only a general description will be given of the apparatus shown, except those parts of it to which the present improvements relate, reference being made to the aforesaid application of George S. Tiffany for a detailed description of other parts of the apparatus.

Each station comprises a transmitter and a receiver, and in the number, relative arrangement and construction and operation of parts, one station is the counterpart of the other. Therefore, in the following description references will be made to either station according as convenience in tracing circuits may dictate, corresponding reference numerals being used in both figures of the drawings, followed, however, in Fig. 2 by the reference letter "a."

Each transmitter comprises a pair of rheostats 1, 2, included in a normally open local circuit, and a source of electric energy, for example, a motor generator 3, the negative pole of which is grounded at 4, this local current-supplying circuit being controlled by a master switch mechanism 5 as a whole, controlling contacts 8, 36, 40, which normally occupy the position in which they are shown in Fig. 2, in which position the station is in receiving condition, and when out of that position occupy the position in which they are shown in Fig. 1, where the station is in transmitting condition. Contact 8 in the position in which it is shown in Fig. 1, closes a circuit from generator 3, traced as follows: wire 6, contacts 7, 8, wires 9, 10, 11 to right rheostat 1, and from wire 11, by wires 12, 13, 14 to left rheostat 2, and from right rheostat 1, by wires 15, 16, and, from left rheostat 2, by wires 17, 18, 16, to the negative pole of generator 3. When contact 8 is in this position, contacts 36, 40 engage stationary contacts 43, 44, thus closing right and left line tracer circuits from the transmitter of such station to the receiver of the distant station, as well as to its own receiver. This is so fully described in the aforesaid application of George S. Tiffany that it will be unnecessary to describe it here beyond merely tracing the right and 110

- left circuits, as thus closed, from the right and left rheostats 1, 2, of the transmitter of Fig. 1, to and through the receiver of Fig. 2, namely, the receiver of the distant station. Such circuit for the right line consists of contact 19, tracer arm 21, wire 47, secondary winding 48 of an induction coil, wire 50, contact 43, contact 36, wires 37, 38, 39 (Fig. 1), wires 39^a, 38^a, 37^a, contact 36^a, contact 45^a, wire 51^a, right relay 52^a, wire 53^a, pen moving coil 54^a, wires 55^a, 56^a, and 16^a, to ground at 4^a Fig. 2. Such circuit for the left line consists of contact 20, tracer arm 22, wire 57, secondary winding 58 of the induction coil, wire 59, contacts 44, 40, wires 41, 42 (Fig. 1), wires 42^a, 41^a, contacts 40^a, 46^a, wire 60^a, relay 61^a, wire 62^a, pen moving coil 63^a, and wires 64^a, 65^a, and 16^a, to ground at 4^a.
- It will be understood, of course, that, as fully described in the aforesaid Tiffany application, as the transmitting tracer 23 is moved laterally in writing, currents, varying in strength in accordance with the position of the contacts 19, 20, lengthwise of the rheostats 1, 2, will be shunted into the right and left main line circuits just described; that the coils 54^a, 63^a, of Fig. 2 will be moved rectilinearly thereby, against the tension of springs (not shown) tending to move them in the opposite direction, on the core 72^a of the magnet 70^a, which, with its pole pieces, 71^a, provides a suitable magnetic field for such coils, which field is excited from the generator 3^a through a local circuit consisting of wire 6^a, contact 7^a, wire 92^a, wire 93^a, lock magnet 94^a, of a unison switch group fully described in the aforesaid Tiffany application, wires 95^a, 96^a, 97^a, 98^a, 99^a, windings 100^a, 101^a, of field magnet 70^a, wires 102^a, 103^a, 104^a, spring contact 105^a mounted on but insulated from armature 106^a of left hand local circuit controlling relay 61^a, contact 107^a, wires 108^a, 65^a and 16^a, to the negative pole of the generator 3^a. This circuit is opened and closed, at a given station (as Fig. 2), at the contacts 105^a, 107^a, and is closed when another station (as Fig. 1) is transmitting to it and current is therefore on the left main line just described from such other station; relay 61^a being then energized and attracting its armature 106^a which moves contact 105^a, into engagement with contact 107^a. The rectilinear movement just referred to, of the coils 54^a, 63^a will depend, in extent and direction, upon the strength, from time to time, of the currents traversing the right and left lines, and will effect, in turn, through connections which are generally shown but need not be specifically described here, lateral movements of the receiving pen 33^a corresponding, in direction and extent, to the lateral movements of the transmitting tracer 23; all as fully described in the afore-
- said Tiffany application. Frictional resistance to movement of the coils 54^a, 63^a, and of the other pen moving parts, is, of course, met with, and to overcome it, various devices and expedients have been resorted to. The present invention relates to means for overcoming such frictional resistance, as before indicated. The means provided consists of a short circuiting buzzer, the magnet 240^a of which is located in the receiving instrument and included in a branch of the local circuit hereinbefore described, for exciting field magnet 70^a, consisting of wire 241^a from said magnet, wires 242^a, winding of buzzer magnet 240^a, wires 243^a, 244^a, and thence by wires 103^a, 104^a, contacts 105^a, 107^a, and wires 108^a, 65^a, and 16^a, of the field magnet circuit, to the negative pole of generator 3^a. This branch circuit, with the field magnet circuit, is closed only when writing currents are on line from the distant station, when by the energization of relay 61^a contacts 105^a, 107^a engage. A shunt, consisting of wire 245^a, armature 246^a of magnet 240^a, contact 247^a, wire 248^a, is formed, in this branch circuit, around magnet 240^a. When, therefore, said magnet is energized and attracts its armature 246^a, such armature, by engagement with front contact 247^a will short circuit magnet 240^a. The latter will then release its armature 246^a, thus breaking this shunt circuit and re-establishing the circuit through the magnet; and so on, so long as the local circuit through field magnet 70^a is closed. As the winding 101^a is in multiple with buzzer 240^a it follows that this winding will also be short circuited by armature 246^a when it engages front contact 247^a. Therefore, the magnetic field in which the coils 54^a, 63^a are located will be maintained in a vibratory condition, which condition will be communicated by the coils to the parts connected therewith, so that the whole pen moving group will be maintained in a vibratory condition, thereby greatly reducing frictional resistance to their movement. Although the description of these vibrating means has been directed specifically, by reference characters, to Fig. 2, because that station is shown as receiving, it will, of course, be obvious that it is equally applicable to Fig. 1, assuming that to be in receiving condition. It will also be understood that, as the local receiver of a station transmitting is also operating like the distant receiver, the pen moving parts will be vibrated in precisely the same way, and by corresponding means, as those of the distant receiver.
- The system as thus far described provides merely for the lateral movements of the receiving pen 33^a. Means are, of course, provided for effecting its movements to and from the record strip as the transmitter tracer is so moved. The means shown here

for such purpose are fully shown and described in the Tiffany patent and Tiffany application aforesaid, so that here they need only be briefly described. They include 5 (referring, for convenience, specifically to Fig. 2), a polarized pen-lifter relay 114^a, a loose contact group 113^a, mounted on a diaphragm 151^a, which is vibrated by relay 114^a when the transmitter tracer rests upon and 10 depresses transmitter platen switch 125, and a pen-lifter magnet 110^a, which is energized and deenergized by relay 114^a; so as to cause the receiving pen to move, respectively, from and toward its record strip. The pen-lifter magnet 110^a is included in a branch 15 of the field-magnet local circuit heretofore described, such branch circuit being traced as follows: wire 111^a from field magnet 70^a, pen-lifting magnet 110^a, wire 112^a, loose contact group 113^a, wires 115^a, 104^a, contacts 105^a, 107^a, and wires 108^a, 65^a, and 16^a, to the negative pole of generator 3^a. The loose contact group 113^a includes a pair of contacts 126^a, 127^a, the inner ends of which engage and one of which is vibrated relatively to the other when a vibrating current passes through relay 114^a so as to, in effect, break this circuit, thus deenergizing pen-lifter magnet 110^a, with the result that the receiving pen 33^a is then moved into contact with its record strip. It will be understood, of course, that at other times, during a transmitting operation, the contact 126 or 126^a is not so vibrated; that pen-lifter magnet 110^a is, therefore, energized, and that receiving pen 33^a is moved away from its record strip. It will also be understood that these movements of the receiving pen 33^a to and from its record strip will take place 40 as the transmitter tracer 23 is so moved by the operator. This is brought about by the provision at the transmitter station, of a short circuiting buzzer 129 (Fig. 1) included in a branch circuit leading from 45 wire 12 of the current-supplying circuit heretofore referred to; this branch comprising wire 130, whence it takes two paths, one consisting of wires 131, 132, 133, primary winding 134 of the induction coil here- 50 tofore referred to, wires 135, 136, resistance 137, and wire 138 to the negative pole of generator 3; and the other consisting of wire 139, magnet 129, wires 140, 141, 142, 136, resistance 137, and wire 138 to the negative 55 pole of generator 3. This two-path branch circuit is normally, and while the transmitter tracer 23 is raised from platen contact 125, shunted out of the current-supplying circuit from generator 3 by a short 60 circuit consisting of wire 143 from wire 12, platen contact 125, contact 144, and wires 145, 142, 136, 138 to negative pole of generator 3. Through these connections, as platen switch 125 is depressed in writing, 65 vibrations are produced in the right and left tracer lines to the distant and local receivers, these producing, through pen-lifter relay 114^a (the winding 149^a of which is bridged across the right and left lines by wire 150^a including a condenser), vibration 70 of diaphragm 151^a and of the loose contacts 126^a, 127^a, in tube 128^a, so as to break the circuit, heretofore described, through pen-lifter magnet 110^a, which is thus deenergized, permitting receiver pen 33^a to move 75 into contact with its record strip. All this is so fully described in the aforesaid Tiffany application that further description here is deemed to be unnecessary.

Where, as in the present case and in the aforesaid Tiffany application, a current generator, as 3, is employed as the source of current supply for the main lines, it has been found that alternating waves or surges are given off by the generator which seriously interfere with the accurate operation of the pen-lifter relay 114^a, which is kept thereby in a constant state of vibration. These are due to many causes, including imperfect setting of contact brushes; rough commutator; dirt on the commutator; sparking at the brushes; etc. To some extent this wave difficulty may be avoided by adjusting the relay 114^a so as to render it non-sensitive to such waves, but this is an unsatisfactory solution 80 of the difficulty because of resulting decreased efficiency in operation. This objection may also be avoided to some extent by loading the generator with a considerable non-inductive load sufficient to absorb the waves, but this is also objectionable because of waste of current, where, as in telautographs, the sole function of the generator is to supply current for the operation of the apparatus. I have discovered that the difficulty may be entirely avoided without resort to these unsatisfactory expedients by connecting across the dynamo terminals a condenser 260 of proper capacity to absorb such waves, as shown in Figs. 1 and 2. The necessary or desired capacity of the condenser for this purpose may be ascertained in several ways, as, for example, by connecting a telephone receiver in series with a small condenser, across the generator terminals and gradually adding condensers to the surge bank until the noise in the receiver disappears or is sufficiently reduced. For generators of one-half horse power or less, a condenser capacity of 18 to 30 microfarads 95 is usually sufficient.

What I claim is:

1. In a telautographic system the combination with the main line wires connecting a transmitter and receiver, of a suitable magnetic field, means including pen members movable in said field by the currents on the main lines, for moving the receiving pen laterally, a short circuiting buzzer connected with the pen moving means for vibrating 110 115 120 125 130 135 140 145 150

the same, and a local circuit in the receiver including said buzzer, substantially as described.

2. In a telautographic system the combination with the main line wires connecting a transmitter and receiver, of a suitable magnetic field, means including pen members movable in said field by the currents on the main lines, for moving the receiving pen laterally, a short circuiting buzzer connected with the pen moving means for vibrating the same, and a local circuit in the receiver including said magnet field and buzzer, substantially as described.
3. In a telautographic system the combination with the main line wires connecting a transmitter and receiver, of a suitable magnetic field, a local circuit for exciting said field, means, including members movable in said field by the currents on the main lines, for moving the receiving pen laterally, a short circuit buzzer connected with the pen-moving means for vibrating the same, and a branch circuit for said buzzer for said local circuit, substantially as described.

4. In a telautographic system, the combination with the main line wires connecting a transmitter and receiver, of a direct current generator for supplying current thereto, a shunt circuit connected to the generator terminals, and a condenser in said shunt circuit and proportioned so as to shunt circuit the injurious alternating currents produced by the generator armature.

5. In a telautographic system, the combination with the main line wires connecting a transmitter and receiver, of a direct current generator for supplying current thereto, a shunt circuit connected to the generator terminals, and a condenser in said shunt circuit and proportioned so as to shunt circuit the injurious alternating currents produced by the generator armature.

In testimony whereof, I have hereunto set my hand, in the presence of two subscribing witnesses.

HENRY W. O'NEILL.
